UNITED STATES PATENT OFFICE.

LAFAYETTE HOLT, OF BURLINGTON, NORTH CAROLINA, ASSIGNOR OF ONE-HALF TO
EUGENE HOLT, OF BURLINGTON, NORTH CAROLINA.

TANK CLOSURE OR COVER.

1,241,735.

Specification of Letters Patent.

Patented Oct. 2, 1917.

Application filed June 10, 1915. Serial No. 33,337.

To all whom it may concern:

Be it known that I, LAFAYETTE HOLT, of Burlington, in the county of Alamance and State of North Carolina, have invented certain new and useful Improvements in Tank Closures or Covers; and I do hereby declare the following to be a full, clear, and exact description of the invention, such as will enable others skilled in the art to which it appertains to make and use the same.

My invention relates to a novel form of cover or closure for a tank opening, and it is particularly applicable to those types of tanks in which it is desired to maintain the contents of the tanks under pressure.

One of the objects of my invention resides in the provision of a single form of cover or closure which can be adjusted to the closing position, or to the opening position, by a single movement of a single member, and also means are provided for clamping the cover in the closing position.

Another object of my invention is in the provision of radially arranged clamping members movable into and out of clamping position, and means for simultaneously moving all of said clamping members.

Also a still further object of this invention resides in the provision of means for finally setting each individual clamping member so that the closing pressure at all points of the cover may be adjusted to compensate for variations in the thickness of the packing ring or gasket which is placed therebeneath.

I will now proceed to describe my invention more in detail with particular reference to the apparatus illustrated on the accompanying drawing, which is illustrative of certain embodiments thereof which I have found in practice to give good results.

In the drawings:

Figure 1 is a top plan view of the cover or closure.

Fig. 2 is a fragmentary diagrammatical view of the same taken on the section line 2-2 of Fig. 3; and

Fig. 3 is a sectional elevation on the line 3-3 of Fig. 1.

As shown in the accompanying drawing the closure is applied to a tank having a flanged neck surrounding the opening therein, but it is to be understood that I do not limit this invention in any sense whatsoever to its application to this particular type of tank.

The upper head of the tank is indicated at 1 and is provided with an opening 2 surrounded by a flange member 3 carrying an overhanging lip 4, the latter being radially slotted as shown at 5 and upon this lip rests 60 a packing ring or gasket 6 of suitable thickness.

The cover or closure proper is indicated at 7 and is provided on its lower surface with a centering ring 8, the diameter of this 65 centering ring being substantially the same as the diameter of the opening 2 in the tank.

Peripherally of the lip 4 are arranged a series of radially extending slots, the purpose of which will be hereinafter set forth. 70 Superposed upon the top surface of the lip 4 is the cover 7 which is provided with a series of apertures 9 registering with the slots in the lip 4. These slots are however extended beyond the lip 4 and mounted therein 75 for sliding movement are clamping members 10 which comprise a squared portion 11 slidable in the slots in the lip 4, a lower head end 12 which is adapted for engagement with the under-surface of the lip 4, and stems 80 13 which extend through the apertures in the cover 7 and are threaded for purposes to be hereinafter described.

Superposed upon the top of the cover 7 is a rotatable member 14 which is pivoted to 85 the said cover 7 at its center as shown, the eye bolt 15 serving as the pivot. This member 14 is provided with angularly extending apertures or slots 16 which correspond in number with the slots in the lip 4 and with 90 the apertures in the cover 7. The threaded stems 13 of the clamping members extend through these apertures 16, and engage a nut portion 17 provided with a hand-wheel 18 for tightening the clamping members in 95 place. The nut portions 17 are engaged by the slots or apertures 16, and thus it will be seen that, by reason of the angular arrangement of these apertures 16, when the member 14 is rotated the clamping members, if 100 loosened, will move inwardly and outwardly in the slots in the lip 4 and apertures in the cover 7, depending upon the direction of rotation of the member 14. In order to provide convenient means for rotating the 105 member 14 a handle 19 is provided thereon.

Due to the fact that the radial apertures 9 in the member 7 are of less width than the nut portions 17 slidably guided in the slots 16 the said portions 17 ride on the upper 110

surface of the cover 7 which forms the support against which the clamping thrust is directed when the hand-wheels 18 are turned to a clamping position.

5 Referring particularly to Figs. 1 and 2, in the former figure the position in which the clamping members engage the lip 4 is shown in dotted lines, and the position in which the clamping members do not engage 10 the lip 4 is shown in dotted lines in Fig. 2. It will thus be seen that by rotating the member 14 in the direction indicated by the arrow in Fig. 1 the clamping members will be simultaneously moved into engagement 15 with the lip 4, and they may be then tightened or set into place by adjusting the hand-wheels 18. However, if it is desired to loosen and remove the cover 7 the hand-wheels 18 are first loosened and the member 20 14 is then rotated in the direction indicated by the arrows in Fig. 2. This operation will withdraw the clamping members from the slots in the lip 4 and the cover 7 may then be removed by suitable means hooked in the 25 eye bolt 15.

While I have described certain embodiments of my invention, in the foregoing specification, it will be understood that variations and modifications can be made there- 30 in, without departing from the spirit and scope of the invention as set forth in the accompanying claims.

I claim:

1. The combination with a tank having an 35 opening, of a flanged member surrounding said opening and having peripheral slots, means for closing said opening including a cover plate having apertures therein corresponding with the slots in said flanged member, cover clamping members loosely carried in said apertures for movement into and out of engagement with said flanged member, means for simultaneously moving all of said clamping members into and out 40 of said slots, and means for securing said clamping members in the inward position, substantially as described.

2. The combination with a tank having an opening, of a flanged member surrounding said opening and having peripheral slots, means movable in a plane parallel with said cover for closing said opening includ- 50

ing a cover having apertures therein corresponding with said slots, cover clamping members having squared shanks slidable in 55 said apertures and slots for movement into and out of engagement with said flanged member, means for simultaneously moving all of said clamping members, and means for securing said clamping members in the inward position to retain said cover in place, substantially as described.

3. The combination with a tank having a circular opening, of a flanged member surrounding said opening and having radially extending peripheral slots, means for closing said opening including a cover having radially extending apertures corresponding with said slots, cover clamping members movable in said apertures and slots for movement into and out of engagement with said flanged member, and a rotatable member superposed on said cover and having spirally arranged slots engaging said clamping members to move the latter in said apertures and slots, and means for securing said clamping members in the clamped position, substantially as described.

4. In combination with a tank opening having a flange provided with slots, a cover having apertures registering with said slots, a superposed rotatable member having slots at an angle to the said apertures, and clamping means extending through said cover and member and engaged by the slots in the latter to move said clamping means into and out of engagement with said flange.

5. In combination with a tank having a flanged opening provided with slots, a cover having apertures extending beyond said flange and registering with said slots, and clamping means movable in one direction in said apertures and slots to engage said flange and also movable in a reverse direction beyond said flange to permit removal of 95 said cover.

In testimony whereof, I have signed this specification in the presence of two subscribing witnesses.

LAFAYETTE HOLT.
